ELECTRICAL CONNECTOR

Charles E. Wade, Sturgis, Mich.

Application May 2, 1940, Serial No. 333,017

18 Claims. (Cl. 173—328)

The present invention relates to electrical connectors, and in particular is directed to improved means for forming a readily made connection between one or pairs of terminals, each terminal being permanently attached to the end of an associated wire.

The principal objects of the present invention are to provide electrical connectors of the above indicated type, which, in certain aspects, are improvements upon the structures described and claimed in applicant's copending application Serial No. 289,017, filed August 8, 1939, now Patent No. 2,360,917, granted October 24, 1944; to provide such structures which can be economically manufactured and assembled, and which are extremely reliable and efficient in operation, and enable the connection between two wires to be readily made; to provide such structures comprising a housing member adapted to receive a contact, the contact being particularly characterized as defining a pair of receptacles each adapted to receive a blade-like terminal; to provide such constructions wherein each contact is formed of two separate contact elements arranged in back-to-back relation and interlockingly held within the housing; to provide such constructions embodying improved means for guiding an associated terminal into the space between the spaced leg portions of the contact; to provide such constructions wherein each contact is formed of a unitary sheet of metal formed to define receptacles of the above mentioned type; and to generally improve the construction and arrangement of electrical connectors of the above indicated type.

With the above as well as other objects in view, which appear in the following description and appended claims, preferred but illustrative embodiments of the invention, as shown in the accompanying drawings, throughout the several views of which corresponding reference characters are used to designate corresponding parts and in which:

Figure 1 is a view in perspective of one embodiment of the invention;

Fig. 2 is a view in longitudinal center section, taken along the line 2—2 of Figure 1;

Fig. 3 is a view in vertical transverse section, taken along the line 3—3 of Figure 2;

Fig. 4 is a perspective view of one of the contact elements constituting the electrical contact in the embodiment of Figs. 1, 2, and 3;

Fig. 5 is a perspective view of a blade-like terminal adapted to cooperate with the connector of the present invention;

Fig. 6 is a sectional view illustrating a modification of the arrangement of Figs. 1 through 4;

Fig. 7 is a view in longitudinal center section of a further modification of the invention;

Fig. 8 is a view in vertical transverse section, taken along the line 8—8 of Fig. 7;

Fig. 9 is a perspective view of one contact element employed in the embodiment of Figs. 7 and 8;

Fig. 10 is a view in longitudinal center section of a further modification of the invention;

Fig. 11 is a view in vertical transverse section, taken along the line 11—11 of Fig. 10;

Fig. 12 is a perspective view of the contact employed in the embodiment of Figs. 10 and 11;

Fig. 13 is a view in longitudinal center section of a further modification of the present invention;

Fig. 14 is a view in perspective of one of the contact elements employed in the embodiment of Fig. 13; and

Fig. 14A is a view in transverse section, taken along the line 14A—14A of Fig. 13.

In the embodiment of Figs. 1 through 4, the present connector comprises a housing 20, molded or otherwise formed of insulating material, and a contact member 22, constituted by two similarly formed elements 24 and 26, which are received within the body of the housing 20 in back-to-back relation.

The housing 20 is provided with a bore extending entirely therethrough, and the respectively opposite ends of this bore are counterbored so as to define enlarged bore portions 28 and 30, and an intermediate restricted bore portion 32. The bore portions 28 and 32 are joined by an annular shoulder 34, and the bore portions 30 and 32 are joined by an annular shoulder 36.

The contact element 24 is illustrated as formed of a single piece of suitable conducting material having spring-like characteristics. The element 24 has a relatively wide central body portion 40, provided with laterally spaced longitudinally extending stiffening ribs 42, and has relatively narrower end portions 44 and 46, which are reversely bent, and the marginal end portions 48 and 50 whereof are slightly outwardly turned, so as to constitute abutments to cooperate with the shoulders 34 and 36, respectively. Intermediate its ends, the central body portion 40 is provided with laterally opposite, outwardly struck portions 52 and 54, which cooperate with the side walls of the restricted bore portion 32, as hereinafter described. The contact element 24 is also provided with longitudinally spaced tongues 56, which are struck inwardly from the body portion 40, and

which are disposed to cooperate with an opening or recess 58 formed in the body of an associated spade-type terminal 60, so as to hold the terminal in place, as described below. It will be appreciated that the contact element 26 preferably duplicates the contact element 24.

The present connector may be assembled in various ways, but in the preferred mode of assembly, a pair of contact elements 24 and 26 are arranged in back-to-back relation to each other and are thereafter inserted together into the body of the housing 20, from either end thereof. During the entry of the contact elements 24 and 26, the leading rounded end portions, such as (a) (Fig. 2), engage one of the shoulders 34 and 36 (in this case, shoulder 34) and continued entering movement causes the reversely turned leg 46 of the element 24 and the corresponding leg 62 of the contact element 26 to be cammed or sprung inwardly towards each other by an amount sufficient to enable the abutment portions 50 and 64 to pass through the restricted bore portion 32. When the contact reaches a centered position within the housing 20, the abutment portions 50 and 64 reach the shoulder 36, thereby enabling the leg portions 46 and 62 to spring outwardly, bringing the abutments 50 and 64 to the positions shown in Fig. 2, in which they are solidly interlocked behind the shoulder 36. At the same time, the abutments 48 and 66 occupy a position in substantial abutting engagement with, and in solid interlocking, relation behind, the shoulder 36.

In the thus assembled condition of the contact and the housing, the stress in the reversely turned end portions *a* and *b* forces the backs of the contact elements 24 and 26 towards each other, bringing the tongues 56 on the contact element 24 and the corresponding tongues 68 on the contact 26 into abutting engagement with each other, so that the contact elements 24 and 26 are securely held in place within the housing, even though no terminals, such as 60, are introduced into the space between the contact elements 24 and 26.

It will thus be seen that the generally blade-like contact elements 24 and 26 define between them a pair of end receptacles or recesses to receive associated blade-like terminals 60. In introducing a terminal 60 into the space between the contact elements 24 and 26, it will be understood that these elements are spread apart, which action decreases the spacing between each reversely turned leg portion, such as 46, and the adjacent intermediate body portion, thereby increasing the stress in the reversely turned end portions and causing the contact elements to firmly grip the terminal between them. The wedging action imposed on the contact elements by the reversely turned end portions is particularly effective adjacent the outer ends of the contact and in the present instance, this wedging action is supplemented by the wedging action afforded by the projections 52 and 54, which act to impose a correspondingly substantial wedging action between the intermediate body portions of the contact elements. The proportioning of the parts is preferably such that when the contact elements lie in back-to-back relation with the tongues 56 and 68 in abutting engagement with each other, the shoulders 52 and 54 on element 24, and the corresponding shoulders 70 on element 26, more or less freely abut the side walls of the intermediate bore portion 32. With this relation, when a terminal 60 is inserted between

the contact elements 24 and 26, thereby spreading them apart, the shoulders 52, 54 and 70 are forced into solid abutting engagement with the just-mentioned wall portions and are sprung to some extent.

When in use, accordingly, the contact elements 24 and 26 have a solid but resilient bearing engagement with substantially the entire surface area of each associated terminal 60, thus affording a very good electrical contact. In service, also, the tongues 56 and 68 project into the previously mentioned openings 58 in the associated terminal 60, thus forming a detent connection between the contact and each terminal.

15 A further feature of the present construction resides in providing means to positively guide each terminal 60 into the space between the contact elements 24 and 26, so as to overcome any otherwise existing possibility of inserting a terminal between one of the contact elements and the adjacent wall of the housing. In the arrangement of Figs. 1 through 4, this is accomplished by forming the reversely turned leg portions, such as 44 and 46, somewhat narrower than 20 the main body portions of the contact, and by forming the side walls of the housing in such relation that such side walls occupy a substantial part of the corner areas thus produced. More specifically, and as more clearly appears in Fig. 3, 25 the opening in the housing 20 is hexagonal in form, so that the side wall portions, such as 30a, extend diagonally from the marginal edge of the intermediate body portion and the marginal edge of an adjacent leg portion. It will be appreciated 30 that the intermediate body portion of each contact is dimensioned to have substantially the same width as the associated terminal 60, so that each such terminal 60 is of greater width than the leg portions, such as 44 and 46, and is also 35 of greater width than all portions of the bore except those portions which are in alignment with the space between the contact elements 24 and 26. In applying a terminal 60 to the connector, accordingly, the end of the terminal can 40 be introduced into the corresponding bore 28 or 30, only in such a position as brings the end of the terminal into alignment with the space between the contact elements, whereby the terminal is positively guided into such space.

50 50 The structure described with reference to Figs. 1 through 4 obviously provides means for connecting two wires together. It will, however, be appreciated that the present connector may be made to afford a connection between any desired 55 number of pairs of wires, in, for example, the manner shown in Fig. 6, in which the housing 80 is formed to provide two bores 82, each whereof receives a contact 84. It will be understood that the individual bores 82 may have the same form and arrangement as the bore described with reference to Figs. 1 through 4, and it will be further understood that the contacts 84 may be formed as described with reference to the contact 22.

65 65 In the modified embodiment of the invention shown in Figs. 7, 8 and 9, the housing 20' is formed to define the enlarged end bore portions 86 and an intermediate smaller bore portion 88, which bore portions are joined by annular shoulders 89, corresponding to the previously described shoulders 34 and 36. The housing 20' receives a contact constituted by a pair of spaced contact elements 90 and 92 arranged in back-to-back relation to each other, and adapted to receive between them corresponding blade-like termi-

nals 60', corresponding to the previously described terminal 60. The contact element 90 is provided with intermediate body portions 94 and 96, a central rib 98, and reversely turned leg portions 100 and 102. The contact 90 is also provided with tongues 104 struck inwardly from the back thereof for cooperation with the opening in the associated terminal. The contact element 90 is similarly formed and it will be understood that the assembly of the elements 90 and 92 in the body of the housing 20' is preferably effected in the previously described manner. When assembled within the housing, the abutments formed at the ends of the reversely turned leg portions engage over the shoulders 89 in the previously described manner, and the stresses in the leg portions hold the tongues, such as 104 and 106, in abutting relation to each other. In this case, the central lateral edge portions of the central ribs 98 and 108 perform the same function as the previously described shoulders, such as 52 and 54. Accordingly, when the contact is initially received within the housing 20', the ribs 98 and 108 more or less freely abut the inner surface of diametrically opposite, longitudinally extending ribs 110, formed in the housing 20'.

In the present instance, in order to positively guide the terminal, such as 60', into the space between the contact elements, the reversely turned legs 100 and 102, and 112 and 114 are slotted, as clearly appears in Fig. 9, the width of each slot being proportioned to relatively freely accommodate the corresponding housing rib 110. The ribs and slots thus do not interfere with the free assembly of the contact within the housing, but, when the parts are in the assembled position (Fig. 8), the ribs 110 provide abutments which act to guide the terminal 60' into the space between the contact elements. Preferably, and as shown in Fig. 7, the outer ends 116 of the ribs 110 are rounded, so that these rounded ends act as guide surfaces to cam the terminals into proper alignment with the contact elements.

In all other respects except those just noted, the construction, arrangement and operation of the embodiment of Figs. 7, 8, and 9 preferably correspond to the embodiment of Figs. 1 through 4.

In the embodiment of Figs. 10, 11 and 12, the contact 120, which is received within a housing 122, is formed from a single unitary piece of stock, as distinguished from the two similar contact elements previously described. In this instance, the housing 122 is provided with a bore 124 of uniform size throughout its lengths except for an abutment 126 formed in one side thereof, which abutment, with the adjacent bore portions, defines the spaced outwardly presenting shoulders 128.

The contact 120 has an intermediate body portion 130, the respectively opposite end portions 132 and 134 whereof are outwardly flared. The contact 120 also comprises the laterally spaced body portions 136 and 138, which are connected to the body portion 130 but in offset relation thereto by ribs 140 and 142. The respectively opposite ends of the portions 136 and 138 are joined by reversely turned portions 144 and 152, the marginal edges whereof are outwardly bent to define abutments 146 and 154.

The spaced portions 136 and 138 and the corresponding end portion 132 define between them a receptacle to receive and yieldingly hold an

associated blade-like terminal 60''. A corresponding receptacle is formed in the other end of the contact by the spaced portions 136 and 138 and end portion 134.

The contact 120 may be assembled in the housing 122 from either end thereof. Assuming the contact is introduced from the lefthand end of the housing, as viewed in Fig. 10, the entering movement brings the reversely turned end 144 into engagement with the shoulder 128, so that further entering movement cams the portion 144 and the portion 134 towards each other. The final entering movement enables the abutment 146 to pass behind and in interlocking engagement with the righthand shoulder 128, and also brings the abutment 154 into engagement with or immediately adjacent to the other shoulder 128. Assuming the entering movement is effected from the righthand end, as viewed in Fig. 10, the initial entering movement brings the portion 152 into engagement with the righthand shoulder 128 so that continued entering movement springs the portions 152 and 132 towards each other. The final entering movement brings the abutment 154 behind the lefthand shoulder 128 and also brings the abutment 146 into engagement with or immediately adjacent to the righthand shoulder 128.

It will be appreciated that the proportioning of the parts is preferably such that when the contact is positioned within the housing, the portions 132 and 152 are sprung towards each other and the portions 144 and 134 are sprung towards each other, so that the stresses in these parts serve to hold the abutments 146 and 154 in interlocking engagement with the corresponding shoulders. The relation is also such that the portions 132, 136 and 138 on the one hand, and the portions 136, 138 and 134 on the other hand, are sprung together so as to have a normal spacing less than the thickness of the associated terminals 60''. Accordingly, when the terminals 60'' are introduced into the housing, they spring the corresponding parts away from each other, thus additionally stressing these parts, and causing the contact to wedge the terminals firmly therebetween. This wedging engagement is found sufficient to hold the terminals in place, although it will be understood that each desired detent means corresponds to the previously described tongues 56, etc., and can be utilized to assist in holding the terminals in place relative to the contact.

In the embodiment of Figs. 13 and 14, the housing 160 is formed to have the enlarged bore portions 162 and 164, which are joined by a smaller bore portion 166, in such relation as to define the spaced outwardly presenting shoulders 168 and 170. The housing 160 receives a contact constituted by the similarly formed contact elements 172 and 174, which are arranged therein in back-to-back relation. The contact element 172 comprises a generally planar body portion 176, having portions 178 pressed outwardly from the back thereof for the purpose described with reference to the tongues 56, etc. The contact element 172 is provided with bent end portions 180, and is also provided with intermediate offset portions 182, the marginal ends 184 whereof constitute abutments for cooperation with the shoulders 168 and 170. The contact element 174 is similarly formed, and it will be appreciated that these elements may be assembled within the housing 160 by arranging them in back-to-back relation and inserting them into the housing

from either end thereof. Assuming the contact is inserted from the lefthand end of the housing 160, as viewed in Fig. 13, the entering movement brings the righthand end portions 180 and 190 towards the shoulder 168. In order to cause said end portions 180 and 190 to ride up over the shoulder 168, the body of the insulator is provided with a ramp 192 associated with each shoulder 168. A corresponding ramp 194 is associated with each shoulder 170. The ramps 192 and 194 are slightly narrower in width than the transverse spacing between the fingers 182 on the contact 172 and of the spacing between the corresponding fingers on the contact element 174.

The ramps 192 are thus effective to cause the ends 180 and 190 to ride up over the shoulder 168. At the conclusion of the entering movement, the leading fingers 182 of the contact element 172 and the corresponding fingers of the contact element 174 pass behind the shoulders 170, in straddling relation to the ramps 194. At this time, also, the trailing fingers 182 of the contact element 172 and the corresponding fingers of the contact element 174 freely abut, or are immediately adjacent to the shoulders 168, and these latter fingers also straddle the ramps 192. In the final position of the parts, also, the outwardly turned end portions 180 and 190 of the contact bear against the side walls of the associated bore portions. It will be understood that the proportioning of the parts is such that the free spacing between each end 180 and the corresponding end 190, as well as the free spacing between each finger 182, and a corresponding finger on the other contact element, exceeds the spacing between the associated walls of the housing. Accordingly, the end portions 180 and 190 and the various shoulder engaging fingers are sprung somewhat, and hold the detent portions 178 in solid abutting engagement with each other. The contact is thus firmly held in place within the housing even though no terminals are introduced therebetween. In introducing a terminal, such as 60", into the housing from either end thereof, the tapered bore surfaces, such as 196, cam the leading end of the terminal into the space between the contact elements 172 and 174. The terminal also forces the contact elements apart, further stressing the end portions 180 and 190 and the several shoulder engaging fingers, so that the terminal is firmly wedged in place between the contact elements. In this instance, the ends 180 and 190 serve to cause the end portions of the contact elements to firmly grip the terminal and the associated shoulder engaging fingers 182 perform the same function for the leading end portion of the terminal. The contact elements 172 and 174 thus firmly engage substantially the entire surface of the terminal, thus affording an efficient electrical contact.

Although only several specific embodiments of the invention have been described in detail, it will be appreciated that various and further modifications in the form, number and arrangement of parts may be made without departing from the spirit and scope of the invention.

What is claimed is:

1. In an electrical connector, the combination of an insulating housing having a bore extending therethrough, said bore being formed to provide a pair of longitudinally spaced outwardly presenting shoulders, a contact in said bore comprising a pair of blade-like elements arranged in back-to-back relation so that a blade-like terminal can be inserted between said elements ad-

jacent either end of said housing, each said element having the opposite end portions thereof reversely turned to define abutments to engage said shoulders to hold said contact in place within said housing, each said reversely turned portion being somewhat narrower in width than the adjacent body portion of the corresponding element, and said housing having guide portions at least partially filling the area afforded by said narrowing of said reversely turned portions, so as to guide a said blade-like terminal into the space between said elements.

2. In an electrical connector, the combination of an insulating housing having a bore extending therethrough, said bore being formed to provide a pair of longitudinally spaced outwardly presenting shoulders, a contact in said bore comprising a pair of blade-like elements arranged in back-to-back relation so that a blade-like terminal can be inserted between said elements adjacent either end of said housing, each said element having the opposite end portions thereof reversely turned to define abutments to engage said shoulders to hold said contact in place within said housing, each said reversely turned portion being slotted and said housing having a rib extending into each said slot and serving to guide said blade-like terminal into the space between said elements.

3. In an electrical connector, the combination of a housing having a bore extending therethrough, and having means formed to define longitudinally spaced, outwardly presenting shoulders, a contact received within said bore, said contact comprising two blade-like elements arranged in back-to-back relation so that a blade-like terminal can be inserted between said elements adjacent either end of said housing, and each said element having abutments struck from the body thereof and adapted to engage over said shoulders so as to hold said contact elements in place within said bore.

4. In an electrical connector, the combination of an insulating housing having a bore extending therethrough, said body having in said bore a pair of longitudinally spaced shoulders, facing respectively outwardly towards the opposite ends of the housing, and a pair of similarly formed blade-like electrical contact elements adapted to receive and releasably hold a blade-like terminal inserted therebetween through either end of said housing, each of said elements comprising substantially flat central body portions and end portions which are turned laterally away from the space between said elements, said elements received in said housing with the said central portions thereof disposed in substantially parallel relation and said laterally turned ends defining abutments to engage said outwardly presenting shoulders, and said elements being arranged in back to back relation so that said ends bear against said housing to urge said central portions toward each other.

5. In an electrical connector, the combination of an insulating housing having an opening extending therethrough, a contact in said opening, said contact comprising a pair of separate and freely abutting pieces, arranged in back to back relation, each of said pieces having spaced terminal engaging portions, corresponding said portions on said pieces being adapted to receive and releasably hold a blade-like terminal therebetween, and abutment means on said housing comprising a pair of shoulders spaced lengthwise of the opening and facing outwardly, at least one

of said pieces having parts at the outer ends of said portions which are laterally turned in the same direction, said direction being away from the space between said pieces, said parts being in interlocking engagement with said abutment means on said housing to hold said one of said pieces in place in said housing and said one of said pieces cooperating with the other of said pieces to maintain said other of said pieces in place in said housing.

6. In an electrical connector, the combination of an insulating housing having an opening extending therethrough, a contact in said opening, said contact comprising a pair of separate and freely abutting pieces, arranged in back to back relation, each of said pieces having spaced terminal engaging portions, corresponding said portions on said pieces being adapted to receive and releasably hold a blade-like terminal therebetween, said housing and contact having cooperating interlocking means which act to hold said contact in place in said housing, said interlocking means including yieldable means which enable snap entry of the contact into said housing when said pieces are arranged in back to back relation and simultaneously inserted into said housing.

7. In an electrical connector, the combination of an insulating housing having an opening extending therethrough, a contact in said opening, said contact comprising a pair of separate and freely abutting pieces, arranged in back to back relation, each of said pieces having spaced terminal engaging portions, corresponding said portions on said pieces being adapted to receive and releasably hold a blade-like terminal therebetween, and abutment means on said housing, at least one of said pieces being in interlocking engagement with said abutment means on said housing to hold said one of said pieces in place in said housing and said one of said pieces cooperating with the other of said pieces to maintain said other of said pieces in place in said housing, said pieces including yieldable means which permit snap entry thereof into said housing when said pieces are arranged in back to back relation and simultaneously inserted into said housing.

8. In an electrical connector, the combination of an insulating housing having an opening extending therethrough, a contact in said opening, said contact comprising a pair of separate and freely abutting pieces, arranged in back to back relation, each of said pieces having spaced terminal engaging portions, corresponding said portions on said pieces being adapted to receive and releasably hold a blade-like terminal therebetween, and abutment means on said housing comprising a pair of shoulders spaced lengthwise of the opening and facing outwardly, at least one of said pieces having parts at the outer ends of said portions which are laterally turned in the same direction, said direction being away from the space between said pieces, said parts being in interlocking engagement with said abutment means on said housing to hold said one of said pieces in place in said housing and said one of said pieces cooperating with the other of said pieces to maintain said other of said pieces in place in said housing, said pieces engaging each other prior to the insertion of the terminal therebetween, and by said engagement being effective to maintain at least one of said pieces in said interlocking engagement with said abutment means, whereby to maintain said contact in proper position in said housing.

9. In an electrical connector, the combination of an insulating housing having an opening extending therethrough, a contact in said opening, said contact comprising a pair of separate and freely abutting pieces arranged in back to back relation, each of said pieces having spaced terminal engaging portions, corresponding said portions on said pieces being adapted to receive and releasably hold a blade-like terminal therebetween, abutment means on said housing comprising a pair of shoulders spaced lengthwise of the opening and facing outwardly, each of said pieces having parts at the outer ends of said portions which are outwardly turned in the same direction, said direction being away from the space between said pieces, said parts being in interlocking engagement with said abutment means to maintain said each of said pieces in place in said housing, said pieces engaging each other prior to the insertion of the terminal therebetween to maintain said pieces in interlocking engagement with said abutment means, whereby to maintain said contact in proper position in said housing.

10. In a connector, the combination of an outer body having an opening extending therethrough, said body having means defining at least a pair of shoulders spaced lengthwise of the opening and facing outwardly thereof, and contact means held within the opening, said contact means including a conductive element having a pair of generally planar surfaces spaced lengthwise of the opening for engagement respectively by blade-like terminals projected into the opening through the corresponding ends thereof, said element having parts at the outer ends of said portions which are turned laterally in the same direction, said direction being away from the said terminal engaging surfaces, said parts being continuously engaged behind the corresponding said shoulders and cooperating therewith in retaining said element within said opening, and means associated with said element for holding said terminals in engagement with said surfaces.

11. In a connector, the combination of an outer body having an opening extending therethrough, said body having means defining at least a pair of shoulders spaced lengthwise of the opening and facing outwardly thereof, and contact means including a conductive element having a pair of generally planar surfaces spaced lengthwise of the opening for engagement respectively by blade-like terminals projected into the opening through the corresponding ends thereof, said element having parts at the outer ends of said portions which are turned laterally in the same direction, said direction being away from the said terminal engaging surfaces, said parts being continuously engaged behind the corresponding said shoulders and cooperating therewith in retaining said element within said opening, at least certain of said parts being yieldable so as to permit a snap entry of said element into said opening, during which movement said certain of said parts snap behind in interlocking engagement with the corresponding said shoulder, and means associated with said element for holding said terminals in engagement with said surfaces.

12. In a connector, the combination of an outer body having an opening extending therethrough, said body having means defining at least a pair of shoulders spaced lengthwise of the opening and facing outwardly thereof, and contact means within the opening, said contact means including a conductive element having a pair of gen-

erally planar surfaces spaced lengthwise of the opening for engagement respectively by blade-like terminals projected into the opening through the corresponding ends thereof, said element having parts at the outer ends of said portions which are turned laterally in the same direction, said direction being away from the said terminal engaging surfaces, said parts being continuously engaged behind the corresponding said shoulders and cooperating therewith in retaining said element within said opening, said element having means including said parts for retaining said portions in spaced relation to that part of the wall of said opening which lies between said shoulders so as to enable said portions to be sprung toward said wall part by the insertion of said terminals into engagement with such portions, and means associated with said element for holding said terminals in engagement with said surfaces.

13. The structure of claim 10, wherein said contact means comprises a pair of conductive elements, one whereof has the structure set forth in claim 10 and the other whereof has terminal engaging portions spaced lengthwise thereof which with the said portions of the one element define receptacles to receive said terminals, said elements being structurally separate and in freely abutting relation, said one element being in part at least retained in interlocking engagement with said shoulders by its engagement with said other element.

14. The structure of claim 11, wherein said contact means comprises a pair of conductive elements, one whereof has the structure set forth in claim 11 and the other whereof has terminal engaging portions spaced lengthwise thereof which with the said portions of the one element define receptacles to receive said terminals, said elements being structurally separate and in freely abutting relation, said one element being in part at least retained in interlocking engagement with said shoulders by its engagement with said other element.

15. The structure of claim 12, wherein said contact means comprises a pair of conductive elements, one whereof has the structure set forth in claim 12 and the other whereof has terminal engaging portions spaced lengthwise thereof which with the said portions of the one element define receptacles to receive said terminals, said elements being structurally separate and in freely abutting relation, said one element being in part at least retained in interlocking engagement with

said shoulders by its engagement with said other element.

16. In an electrical connector, the combination of an insulating housing having a bore extending therethrough, a contact in said bore, said contact comprising a pair of separate and freely abutting pieces, arranged in back-to-back relation, each of said pieces having spaced terminal engaging portions, corresponding said portions on said pieces being adapted to receive and releasably hold a blade-like terminal therebetween, and abutment means on said housing, at least one of said pieces being in interlocking engagement with said abutment means on said housing to hold said one of said pieces in place in said housing and said one of said pieces cooperating with the other of said pieces to maintain said other of said pieces in place in said housing.

17. In an electrical connector, the combination of an insulating housing having a bore extending therethrough, a contact in said bore, said contact comprising a pair of separate and freely abutting pieces, arranged in back-to-back relation, each of said pieces having spaced terminal engaging portions, corresponding said portions on said pieces being adapted to receive and releasably hold a blade-like terminal therebetween, said housing and contact having cooperating interlocking means which act to hold said contact in place in said housing, said interlocking means including yieldable means which enable snap entry of the contact into said housing.

18. In an electrical connector, the combination of an insulating housing having a bore extending therethrough, a contact in said bore, said contact comprising a pair of separate and freely abutting pieces, arranged in back-to-back relation, each of said pieces having spaced terminal engaging portions, corresponding said portions on said pieces being adapted to receive and releasably hold a blade-like terminal therebetween, and abutment means on said housing, at least one of said pieces being in interlocking engagement with said abutment means on said housing to hold said one of said pieces in place in said housing and said one of said pieces cooperating with the other of said pieces to maintain said other of said pieces in place in said housing, said pieces including yieldable means which permit snap entry thereof into said housing.
